UNITED STATES PATENT OFFICE.

ALEXANDER MASZCZYK, OF CHICAGO, ILLINOIS.

LOCK.

Application filed October 3, 1924. Serial No. 741,445.

This invention relates to new and useful improvements in locks and more particularly to an especially designed lock for use in retaining the spare wheels on the usual rack provided therefor on motor vehicles. The main object of my invention is the provision of a lock whereby the main locking body is provided with means for locking the same in connection with the attaching nut or releasing the same therefrom whereby the lock body may be readily rotated without in any way imparting movement to the locking nut, thus preventing unauthorized persons from operating the lock and removing the lock from its locking position.

Another object of my invention is the provision of a lock of the above character which can be used equally as well on doors, such as garage doors and the like, and is so constructed as to provide for suitable hand grips for the person desiring to operate the same whereby the lock may be readily detached or attached as desired.

With the above and other objects in view, the invention consists in the novel features of construction, the combination and arrangement of parts hereinafter more fully set forth, pointed out in the claims and shown in the accompanying drawings, in which:

Fig. 1 is a top plan view of a lock constructed in accordance with my invention.

Fig. 2 is a longitudinal section on the line 2—2 of Fig. 1.

Fig. 3 is a horizontal section on the line 3—3 of Fig. 2.

Fig. 4 is a transverse section on the line 4—4 of Fig. 2 and,

Fig. 5 is a detail horizontal section illustrating a slightly modified form of the lock.

Referring more particularly to the drawings, the numeral 1 indicates the body portion of my improved lock which may be of any preferred form and extending from each end thereof are the hand grips 2 preferably tapered toward their outer ends as illustrated in the drawings. The body member 1 has an annular collar 3 extending from one face thereof and extended into the body thru the collar 3 is a bore 4 which is provided with an inner reduced end 5.

Arranged within the bore is the locking drum 6 having an annular enlarged portion 7 which is provided at spaced intervals with cylindrical recesses 8. Surrounding the lock drum and threaded into the outer end

of the bore 4 is a retaining collar 9 the inner end of which abuts against the face of the portion 7 for retaining the drum within the bore 4. From this it will be apparent that the collar 9 and the body portion 1 of the lock may be rotated about the drum while the drum remains stationary.

The locking drum 6 is provided with a central threaded bore 10 adapted to receive the bolt 11 which may be carried by any object to which it is desired to apply the lock and when the drum 6 is threaded on to the bolt 11 the body portion 1 of the lock may rotate upon the drum without moving the drum.

In order to connect the body portion 1 of the lock with the drum 6 for rotating the drum to move the same upon the bolt 11, a locking bolt 12 is provided which is slidably mounted within a bore 13 formed in one of the hand grips 2. The outer end of the bore 13 is normally closed by means of a threaded plug 14. The locking bolt 12 is provided with a transverse recess 15 and movable within this recess is a pin 16 carried by the rotatable lock member 17. This lock member 17 may be of any conventional type wherein a portion thereof is rotatable and connected to this portion which is rotatable, is the pin 16 whereby when a key is inserted in the keyway 18 of the lock, the rotatable portion of the lock will be moved for imparting movement to the pin 16 and reciprocating the bolt 12 in the bore 13 to either project the inner end of the bolt into one of the recesses 8 or remove the same therefrom.

From the above it will be apparent when it is desired to screw the locking drum 6 upon the bolt 11, the lock member 17 is actuated to move the inner end of the locking bolt 12 into one of the recesses 8, thus causing the body 1 and the drum 6 to rotate simultaneously. As the drum 6 has been screwed on to the bolt 11 to the desired locking position the lock 17 is then actuated to disengage the locking bolt 12 from the drum 6 permitting the body member 1 of the lock to freely rotate upon the drum 6 thus preventing the entire lock from being removed from the bolt 11.

The collar 3 is provided with an annular recess 19 and engaged therewith is a ring 20 having an eye 21 whereby a chain or suitable supporting member may be attached to the lock for supporting the same in a con-

venient position with respect to the device to which it is applied.

In Fig. 5 I have illustrated a slightly modified form of the invention wherein the 5 longitudinal bore 13' of the hand grips 2' is provided with an enlarged threaded portion 22 and attached to the outer end of the locking bolt 12' is a threaded head 23 having a transverse slot 24 in which is arranged 10 a pin 25 carried by the rotatable locking member 26. This locking member 26 is rotatably mounted in the outer end of the hand grips 2' and actuated by a predetermined type of key adapted to be inserted in the locking 15 member for rotating the same. From this construction, it will be apparent that when the locking member 26 is operated, the head 23 will be moved longitudinally within the threaded portion 22 causing the inner end of 20 the locking bolt 12' to engage within one of the recesses 8' in the locking drum 6' whereby the drum 6' and the body 1' may be rotated simultaneously. It will also be apparent that upon reverse movement of the locking 25 bolt 12', it will be disconnected from the drum 6' and permit rotation of the body 1' from the drum 6'.

It will be apparent from the foregoing that I have provided a simple and inexpensive lock member which may be quickly and readily applied for preventing the removal 30 of spare wheels from the supporting rack provided therefor on automobiles and the device may be used equally as well on doors 35 and the like so as to prevent access by an unauthorized person.

While I have shown and described the preferred embodiment of my invention, it will be understood that various changes and 40 alterations may be made without departing

from the spirit of the invention or the scope of the appended claims.

Having thus described my invention, what I claim is:

1. A locking device including a body portion having a transverse bore provided with a reduced inner end, a locking drum arranged within the bore with its inner end rotatably mounted in the reduced end, a retaining collar threaded into the bore and embracing the outer end of the drum, an annular enlarged portion on the drum at the inner end of the main bore having cylindrical recesses at predetermined positions in the periphery of the enlarged portion and 50 a locking bolt adapted to be projected into any of said recesses for retaining said drum in place against movement.

2. A lock of the character described including a body having a bore transversely 60 thereof with a reduced inner end, a locking drum arranged within the bore, a collar threaded into said bore and embracing the outer end of said drum the inner end of the said drum being rotatable in the reduced portion of the bore, an annular enlarged portion on the drum between its ends and rotating within the main portion of the bore, said enlarged portion having a cylindrical recess arranged at predetermined points in the 70 periphery thereof, said body having a longitudinal bore adapted to align with any one of said recesses, a locking bolt slidably mounted in the last mentioned bore and manually operated means for actuating said 75 bolt to project one end thereof into any one of said recesses or remove the same therefrom.

In testimony whereof I affix my signature.
ALEXANDER MASZCZYK.
